APPARATUS FOR TREATING RESPIRATORY ORGANS

Magnus W. Larson, Seattle, Wash.

Application March 23, 1939, Serial No. 263,785

4 Claims. (Cl. 128—367)

My invention relates broadly to steam cabinets, and more particularly to a cabinet for medicinally treating infections and disorders of the respiratory organs.

5 An important object of my invention is to provide a cabinet adapted to receive the head of a person suffering from sinus trouble, head colds, catarrh and other diseases of the head, throat, and respiratory tracts, and having means associated therewith to effectively treat the same.

10 Another object of my invention is the provision of means for directing medicated steam or vapor into the respiratory tract of a person suffering from respiratory diseases.

15 Yet another object of my invention is to provide means for medicating the vapor before introducing the same into the cabinet.

20 Still another object of my invention is to provide means to selectively control the temperature within the cabinet.

25 Other objects and advantages of my invention will be apparent during the course of the following description.

30 In the accompanying drawings, forming a part of this specification, and in which like numerals are employed to designate like parts throughout the same:

Figure 1 is a perspective view of a device embodying my invention;

35 Figure 2 is a vertical sectional view of the vaporizer, and showing its association with the cabinet;

Figure 3 is a transverse sectional view, taken on the line 3—3 of Figure 2;

40 Figure 4 is a transverse sectional view, illustrating the deflector embodying a part of my invention;

Figure 5 is an edgewise elevation of the deflector plate;

45 Figure 6 is a transverse sectional view, partly in elevation, illustrating the adjusting screw for selectively positioning the cover of the cabinet with respect to the body thereof, and

Figure 7 is a perspective view of the mixing valve embodying a part of my invention.

50 In the drawings, wherein for the purpose of illustration, is shown a preferred embodiment of my invention, the numeral 10 designates the cabinet in its entirety, including a housing 11, cover 12, vaporizer 13, mixing valve 14 and deflector 15.

The housing 11 is substantially box-like in its construction, having an open bottom and with the front wall 16 thereof recessed, as at 17, to embrace the neck of a person whose head is to be accommodated within the housing 11.

5 The cover 12 is hinged to the rear wall of the housing, and has secured to its outer side thereof a heating element 18, the inner end of which extends through the opening 19. A plurality of flexible wires 20 are positioned circumferentially around the opening 19 with their outer ends joined, as at 21. Disposed within the wires 20, and supported thereby, is a substantially circular deflector 22, of asbestos or the like, to effectively shield the face of a person within the housing 11 from the direct radiations of the heating element. The forward edge of the cover 12 is provided centrally thereof with a swivel screw 23 which is formed with an annular flange 24 rotatably received in a recess 24'. A retaining plate 25 is 10 bolted, or otherwise secured, to the outside of the cover between the flange 24 and head 28 of the screw and prevents the said bolt from being longitudinally displaced from the cover, but permitting the axial rotation thereof. When the cover 20 is in the lowered position the heating element 18 and the wires 20 are received in an opening 29 in the top of the housing 11, and the shank 26 of the screw 23 is received in a screw threaded opening 30 provided in the top adjacent the front wall 16. 25

30 The numeral 31 designates a circular container which is attached to the housing 11 by the threaded pipe 32 and threaded thereon between the walls of the container and the housing is an intermediate nut 33. Nuts 34 and 35 are threaded on the pipe interiorly of the container 31 and housing 32 to securely clamp the same together. The container 31 is formed adjacent its lower end 36 with an annular flange 38 which supports a false bottom 37. A heating element 39 is disposed between diametrically opposed sides of the flange 38 and is connected to an electrical conductor 40 joined exteriorly thereof to any suitable source of electrical power. The container 31 is provided with a disk like cover 41 which is formed at its outer periphery with a depending skirt 42 adapted to embrace the upper end of the container, and with the inner portion thereof bent downwardly and inwardly to form an annular bead 43 adapted to support the cap 44. The cap 44 is provided at its top with an opening 45 through which extends a flexible chain 46 having a ball 47 attached to its outer end to prevent the same from dropping within the container 31 and a foraminated medication container 48 pendulously attached to its lower end. 35

40 The mixing valve 14 is formed with a vertically disposed portion 49 interposed between the nut 35 and the wall of the housing 11. The lower portion 50 of the valve is disposed in acute angu- 45

50 lously attached to its lower end. 50

The mixing valve 14 is formed with a vertically disposed portion 49 interposed between the nut 35 and the wall of the housing 11. The lower portion 50 of the valve is disposed in acute angu- 55

- lar relation therewith, and either edge 51 thereof is curved upwardly and inwardly to form side walls for directing the vapor issuing from the vaporizer 13, through the restricted mouth 52.
- 5 A deflector 15 is positioned in the forward wall 16 of the housing 11 adjacent the top and in alignment with the mouth 52 of the mixing valve 14, to receive the vapors issuing therefrom against the substantially circular deflecting plate 53.
- 10 The plate 53 is formed with a vertically disposed segment 54 to which is attached the shank 55 of a handle 56. The handle 56 is positioned exteriorly of the wall 16 and provides a means whereby the reflector 15 may be manually rotated from a position exteriorly of the housing 11.
- 15 The operation of my device is as follows:

The treatment consists in the application of heat developed and applied through the electric heater 18 mounted on the cover 12 of the cabinet, 20 and by the application of medicated steam or vapor produced in the vaporizer 13 attached to the side of the cabinet. The vapor issuing therefrom passes through the pipe 32 and into the mixing valve 14 where it is thoroughly mixed 25 with the warm air in the cabinet and directed against the deflecting plate 15. The plate 15 is rotatably adjustable so that the vapor may then be directed to the mouth or nostrils of the person whose head is within the cabinet 11. When 30 the heater 18 is energized, and the cover 12 tightly closed, the interior of the housing 11 will become heated, and the desired temperature is maintained by properly positioning the cover. The adjusting screw 23 may be axially rotated 35 to raise or lower the cover to allow heat to escape from within the cabinet or to be retained therein.

A quantity of water is introduced into the container 31, and the desired medication in the container 48. When electric current flows through 40 the heater 39 below the false bottom 37 of the container 31 the water within the container is volatilized, and in rising passes through the foraminated container 48, where it becomes saturated with the medication therein. As the medicated vapor issues from the pipe 32 it is thoroughly mixed with the heated air within the cabinet 11 in passing through the mixing valve 14. The upwardly extending side walls 51 of the valve will direct the vapor through the mouth 52 and against the deflecting plate 53 which may be manually rotated to properly cause the vapor to flow into the mouth and nostrils of the patient.

It is to be understood that the form of my 55 invention, herewith shown and described, is to be taken as a preferred example of the same, and that various changes in the size, shape and arrangement of parts may be resorted to without departing from the spirit of my invention, or the 60 scope of the appended claims.

Having thus described my invention, I claim:

1. A vaporizer comprising the combination of a housing having an open bottom side and a 65 recess in the front wall thereof to receive the

neck of a person, a cover pivotally attached to the housing, a heating element carried by the cover and received within the housing, a screw swivelly connected to the cover and engaging a screw threaded opening in the top of the said housing, a medication container disposed exteriorly of said housing and communicating therewith, a valve member within said housing to mix the medicated vapors issuing from the container with the warm air within the housing, and an adjustable deflector disposed within the housing to direct the vapors toward the mouth and nostrils of the said person.

2. A vaporizer comprising the combination of a housing having an open bottom side and a recess in the front wall thereof to receive the neck of a person, a cover pivotally attached to the housing, a heating element carried by the cover and received within the housing, a screw swivelly connected to the cover and engaging a screw threaded opening in the top of the said housing, a water receiving receptacle exteriorly of the housing and communicating therewith, a cover for the said receptacle, a heating element within said receptacle to volatilize the water therein, a foraminated medication container depending from the cover and above the said water, and means to direct the vapor issuing from the said receptacle toward the mouth and nostrils of the said person.

3. A vaporizer comprising the combination of a housing having an open bottom side and a recess in the front wall thereof to receive the neck of a person, a cover pivotally attached to the housing, a heating element carried by the cover and received within the housing, a screw swivelly connected to the cover and engaging a screw threaded opening in the top of the said housing, a water receiving receptacle exteriorly of the housing and communicating therewith, a cover for the said receptacle, a heating element within said receptacle to volatilize the water therein, a foraminated medication container depending from the cover and above the said water, and a valve member within said housing to mix the medicated vapors issuing from the receptacle with the warm air within the housing, and an adjustable deflector within the housing to direct the vapors toward the mouth and nostrils of the said person.

4. A vaporizer comprising a housing adapted to receive the head of a person therein, a heating element retractively received within said housing, a medication container disposed exteriorly of said housing, a tubular member communicating with the said container and the said housing, an adjustable deflector rotatably mounted in the housing, a handle attached to the said deflector exteriorly of the housing to permit the manual rotation thereof, and a mixing valve within the housing disposed below the said tubular member and having upwardly curved side walls to direct the vapors toward the said deflector.

MAGNUS W. LARSON.
